United States Patent Office.

J. H. SEYMOUR, OF HAGERSTOWN, MARYLAND.

Letters Patent No. 88,220, dated March 23, 1869.

IMPROVEMENT IN WATER-CLOSETS.

The Schedule referred to in these Letters Patent and making part of the same.

To all whom it may concern:

Be it known that I, J. H. SEYMOUR, of Hagerstown, in the county of Washington, and State of Maryland, have invented a new and useful Improvement in Water-Closets; and I do hereby declare that the following is a full, clear, and exact description of the same, reference being had to the accompanying drawings, forming a part of this specification, in which is represented a vertical section of a water-closet constructed according to my improvement.

This invention is especially designed for water-closets to be used in railway-cars and steamboats, and relates to a construction whereby, when the lid is raised, the funnel is closed; and

It consists in a novel arrangement of the parts, whereby the lower trap, or valve is made to open clear of the channel, or passage of the closet, and to this end is provided, at its lower extremity, with a funnel of greater calibre, extending somewhat above the tapering end of the hopper, and effecting a junction therewith by means of an offset in said funnel, so as to correspond in size with that portion of the hopper to which it is secured, in such a manner as to form a recess in the rear portion of the funnel, below the lower extremity of the hopper; into which the said trap, or valve is permitted to open, so as to afford a clear and unobstructed passage through the tube.

In order that others may be better enabled to understand the construction and operation of my improvement, I will proceed to describe it with reference to the drawings.

A is the hopper of a water-closet, the lower portion of which is received within the upper end of a funnel, D, which is so constructed, by means of an offset, F, near the upper extremity, as to afford sufficient space below and in rear of the lower extremity of the hopper A, to effect an unobstructed passage from the hopper and through the funnel D, by the more perfect open-

ing of a trap, or valve, e, hinged to the lower extremity of the said hopper, and which opens back into a recess formed by the offset F.

This trap, or valve e, is connected to the rear and lower extremity of the hopper A, by means of a hinge, h, and operated by a rod, b, pivoted to a projection, f, in rear of the hinge h, and which, passing upward and through an opening, c, in the offset F, is connected, by a joint, d, to the rear portion of a lid, C, on the seat B, in such a manner as that when the lid C is raised, the valve e is closed, and when the said lid is closed, the valve, or trap e, is opened clear of the channel, and back within the offset F.

B is the floor, to which the closet is secured by means of a flange and screws, or by any other suitable arrangement.

A reversed position of the lid C and valve e is illustrated by those parts of the drawing represented in red outline.

I do not claim, broadly, operating the valve by the motion of the cover, as this has been done in various ways before.

I am aware that water-closets have heretofore been constructed so that the valve and cover of the seat shall assume the same relative position, as in the patent of E. Mangeon, dated October 23, 1866. This, therefore, I do not claim.

What I claim as my invention, and desire to secure by Letters Patent, is—

The connection of the valve e with the cover C, by means of the joint d, rod b, and arm f, in such manner that when the cover C is raised, the valve e shall be closed, and *vice versa*; essentially as shown and described, for the purpose set forth.

J. H. SEYMOUR.
